UNITED STATES PATENT OFFICE

WILLIAM H. AMES, OF MARKESAN, WISCONSIN, ASSIGNOR, BY MESNE ASSIGNMENTS,
TO FOOD MACHINERY CORPORATION, OF SAN JOSE, CALIFORNIA, A CORPORATION
OF DELAWARE

GRADING MACHINE

Application filed February 28, 1927. Serial No. 171,574.

This invention refers to an improved machine for grading products of vegetative growth and is particularly adapted to the grading of peas and such small globular materials during the process of canning, it also refers to a new and improved method in the grading operation.

A particular feature of the invention resides in the time the grading is effected relative to the other steps in the preparation of peas or like substances for canning purposes. The operation of grading in this instance is one for quality instead of one for size. The regular grading operation for size is carried out in the ordinary manner and usually follows the shelling or threshing of the peas. My invention contemplates an additional grading operation to improve the quality of the pack by segregating the tender peas from the hard overripe peas of the same or substantially the same graded size.

Every load of peas delivered to the cannery from the field will contain peas of varying degrees of ripeness and of size. The ordinary grading machines are capable of quite effectively grading the peas as to size but no sure and efficient method has heretofore been available for then regrading the peas of a given size for quality, meaning by that, that the tender peas are separated from the overripe and hard peas where all are of substantially the same graded size.

The mature and hard peas can seldom be detected and separated by hand picking and the fact that just a very few hard and mature peas in a can of supposed fancy peas will lower the grade from fancy to extra-standard or standard and thus lower the price has created a desire for some method of grading the pack for quality as well as for size.

I have made the important discovery that after the peas are graded for size and passed through the blancher where they receive a thorough heating that the tender and most choice peas will float while the hard and over-

ripe peas will sink in a properly prepared and maintained brine solution. It of course is old in the art to grade peas for size and then blanch them, but never before, to my knowledge has another grading operation been incorporated in the process after the blanching operation, which grading was for the sole purpose of separating the tender peas from the overripe peas in batches of the same graded size. Brine solutions have been used in attempts to separate the tender from the hard peas previous to blanching but without success. The trouble encountered in such attempts has been due to the fact that the specific gravity of the hard peas is substantially the same as that of some of the tender peas which causes them to float at the same levels and thus defeat separation. In some peas that have been graded for size the specific gravity will be the same for the hard and the tender peas so that here also grading for quality cannot be effected.

The blanching operation, which is in substance a short preliminary cook has the effect of filling the starchy or mature peas with water which immediately changes their specific gravity and causes them to sink in a properly maintained brine solution, in fact this action is so rapid that when a quantity of mixed peas as to quality are dumped into the brine solution, the tender and choice peas, bob to the top and the hard water soaked peas sink immediately giving almost instantaneous separation.

It is not always necessary to grade the peas before blanching, since some varieties may be blanched and graded for quality without a pregrading operation, the whole problem in preparing such varieties for canning being a grading for quality only.

It is therefore a principal object of my invention to provide a method of handling and separating peas whereby the most tender and choice peas will be automatically separated from the more mature and hard peas.

It is also an object of my invention to provide a method of separating the tender from the hard and mature peas after the mass of peas have been graded for size.

5 It is also an object of my invention to provide a method of separating the tender from the hard peas in a mass of the same graded size after the peas have had a preliminary heating.

10 It is also an object of my invention to provide a method of preparing peas for canning wherein an added step of grading is employed to improve the quality of the canned product.

15 It is also an object of my invention to provide a machine for carrying out the method of separating peas for quality as well as for size.

20 It is also an object of my invention to provide an apparatus for receiving a mass of treated peas and separate the tender from the overripe peas.

25 It is also an object of my invention to provide an apparatus for receiving a mass of peas that have been graded for size and to regrade said mass for quality by separating the tender from the hard and overripe peas.

30 It is also an object of my invention to provide an apparatus for grading peas wherein means are provided for automatically segregating the tender from the hard and overripe peas and other means from removing the separated masses from the apparatus.

35 With such objects in view as well as other advantages inherent in the invention, consisting in the parts and combinations hereinafter set forth and claimed, it is understood that the several necessary elements, parts and combinations constituting the same may be varied in their operative relation, proportion and placement without departing from the scope and nature of the invention, and in order to make the invention more clearly understood there are shown in the accompanying drawings means and mechanism for placing the 40 same in concrete form without limiting the improvements in their application to the particular structure chosen to illustrate the invention.

45 Referring now to the drawings a better and clearer understanding of the method and apparatus for carrying out the same will be had.

50 Fig. 1 is a side elevation of the apparatus chosen to illustrate the application of the method.

55 Fig. 2 is an end elevation partly in section as indicated by the line 2-2 of Fig. 1.

Figure 3 is a proposed line up of apparatus including the device of the present application at the left of the assembly. This arrangement shows the relative positions of the several parts of equipment required where grading, blanching and then regrading for quality is adopted. On some varieties of 60 sweet peas the first grading step may be

omitted and the peas graded only after blanching.

The method part of this invention contemplates subjecting a mass of peas or other product of vegetative growth to an added 70 step in the process of preparation for canning. This added step provides a grading operation in a brine solution of suitable gravity for improving the final quality of the pack and is carried out after the mass of 75 peas have been graded for size in the ordinary manner and passed through the blancher, which in substance is a preliminary cooking operation. By blanching the peas before grading for quality the hard overripe peas 80 absorb sufficient water to increase their specific gravity and cause them to sink rapidly when placed in the brine solution, while the blanching of the tender peas does not materially affect their specific gravity so that 85 they will float about the same after blanching as before.

The apparatus part of this invention comprises a machine adapted to carry out the described method and consists of a suitable 90 hopper into which a suitable brine is placed and into which the mass of blanched peas are dumped. Two separate conveying means are provided, one arranged to serve the bottom of the brine tank and pick up the hard 95 water soaked peas that sink and remove them for further treatment in the process of canning, and the other conveyor operating over the surface of the brine and adapted to skim the surface and pick up the tender peas 100 that float and remove them for further treatment.

The numeral 1 represents the hopper for holding the brine solution and for housing the lower end of one of the conveyors. 2 105 indicates the point where the mass of peas are dumped into the hopper, which may be done by a suitable conveyor, not shown, or by hand operation with baskets. 3 indicates the conveyor for removing the peas that sink and is shown as extending down into the lower part of the hopper 1. The arrangement of the buckets on the conveyor 3 is such that they pass in close relation with a deflected wall 4 of the hopper 1 and are thus enabled to pick up and remove all of the peas that sink. The wall 5 of the hopper 1 is for the purpose of preventing the peas that float from coming into contact with the elevator 3, but assists in causing them to be picked up by the buckets of the other conveyor. 6 indicates the conveyor or elevator for skimming the surface of the brine bath through the medium of the buckets 7 and thus picking up the peas that float. This elevator moves in the direction of the arrow "A", and as the buckets 7 reach the top positions the peas are dumped on the conveyor belt 8 and moved to a suitable place of disposal or for further 115 treatment.

The various moving elements receive motion from the drive belt 9, chain 10, pinions 11 and 12, chain 13, chain 14 and bevel gears 15.

5 The buckets 7 are of comb construction to prevent as much as possible agitation of the surface of the brine solution as they pass therethrough. This construction is clearly shown in Fig. 2.

10 Referring now to Figure 3 where is shown an assembly including a first grader 16, a blancher 17 and the regrading machine of the present invention indicated by the numeral 1. This is the arrangement generally adopted for handling the general run of peas, some varieties, however, do not always need the first grading operation in which case they are simply run through the blancher to change the character of those that are over-
15 mature so that they will readily separate from those that are of the desired quality when subjected to the action of the grading machine of the present application.

20 What I claim as new and desire to secure 25 by Letters Patent is:

1. The method of treating peas for canning purposes consisting in subjecting a mixed mass of different size peas to a grading operation that will separate the different 30 sizes into separated groups, subjecting each group to a blanching operation to change the specific gravity of the more mature peas of each group and then subjecting the blanched peas to a grading operation in a 35 suitable brine solution in which the more mature peas will sink and the tender ones float whereby they may be separated into separate groups.

2. An apparatus for separating a mass of 40 peas into groups according to quality comprising means for blanching a mass of peas of a previously graded size, means for then receiving said blanched mass comprising a solution of a predetermined specific gravity 45 wherein said peas will separate into two groups according to their specific gravity, separate means for collecting each group and independently removing them from the said solution.

50 3. An apparatus for grading peas comprising means for receiving a mass of mixed sizes and grading the mass into groups of approximately like sizes, blanching each group to increase the specific gravity of the ripe and mature peas, means for then receiving 55 the blanched mass comprising a solution of a predetermined specific gravity wherein the peas of greater specific gravity will sink and the others float thus forming two distinct groups with means for then removing each group separately.

60 4. A method of treating peas for canning to produce a product of uniform size and quality, which consists in first grading the hard and soft peas to obtain a mixture of

peas of uniform size, blanching said sized mixture to partially cook the same and render the peas sensitive to contact with a liquid, immersing the blanched uniform sized peas in a liquid bath to grade and separate the hard from the soft peas by their relative difference in specific gravity, and separately discharging the hard and soft peas whereby a blanched mixture of soft fancy grade peas of uniform size and quality is obtained.

70 5. The method of treating peas or like materials for canning purposes consisting in subjecting a mass of peas to a blanching operation to change the specific gravity of a part of the mass, then subjecting the mass of blanched peas to a grading operation in a suitable solution wherein those peas that have had their specific gravity changed by the blanching step will sink and the tender soft skinned peas will float whereby the original mass may be removed as separate groups.

75 6. An apparatus for separating a mass of peas into groups of hard and soft peas comprising means for blanching the mass of peas, means for then receiving the mass of 80 blanched peas comprising a solution of a predetermined specific gravity wherein said peas will separate into two groups according to their specific gravity, the heavier ones sinking and the lighter ones floating, separate means for collecting each group and independently removing them from the solution.

85 7. An apparatus for grading a mass of peas for quality and separating the soft from the hard peas comprising means for subjecting a mass of peas to a blanching treatment to increase the specific gravity of the riper and harder peas of the mass, then directing the treated mass to another means comprising a 90 suitable solution in a tank wherein the peas are dumped promiscuously and immediately separate into groups according to their specific gravity, the heavier ones sinking and the harder ones floating, an endless elevator 95 positioned in the tank and adapted to collect the sinkers and remove them, another endless elevator arranged over the said tank and adapted to collect the floaters and remove them, a division wall in said tank separate 100 from the walls of the tank for separating the said elevators so that the separated peas will not become mixed during the removal thereof.

105 8. The method of treating peas or the like material for canning purposes consisting in subjecting a mass of peas to a blanching operation to change the specific gravity between the young and more mature peas, then subjecting the mass of blanched peas to a grading operation in a suitable solution wherein the heavier peas will sink and the lighter ones float whereby the original mass may be removed as separate groups.

110 9. An apparatus for separating a mass of 115

peas into groups of hard and soft peas comprising means for blanching the mass of peas, means for then receiving the mass of blanched peas comprising a solution of a predetermined specific gravity wherein said peas will separate into groups according to their specific gravity, the heavier ones sinking and the lighter ones floating, whereby the original mass may be removed in separate groups.

10 In testimony whereof I affix my signature.
WILLIAM H. AMES.
